US0D1081372S

(12) United States Design Patent (10) Patent No.: US D1,081,372 S
(45) Date of Patent:  Jul. 1, 2025

(54) BOTTLE(71) Applicant: H.J. Heinz Company Brands LLC,
Pittsburgh, PA (US)(72) Inventors: Amy Adriana Wilhelmina Beekmans,
Oirschot (NL); Rudiney Ramos De Souza, Cascais (PT); Verónica Vanhackendover Salgueiro, Cascais (PT)(73) Assignee: H.J. Heinz Company Brands LLC,
Pittsburgh, PA (US)() Term: 15 Years(21) Appl. No.: 29/967,099(22) Filed: Oct. 8, 2024

CLAIM

The ornamental design for a bottle, as shown and described.

DESCRIPTION

FIG. 1 is a top, front perspective view of a bottle in accordance with our new design;

FIG. 2 is a bottom, rear perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof; and,

FIG. 8 is a bottom plan view thereof.

The broken lines shown in the drawings depict portions of the bottle that form no part of the claimed design.
